CLAIM

I claim the ornamental design for a sponge and cleaning pad stand, as shown and described.

DESCRIPTION

FIG. 1 is a perspective view of a new, original, and ornamental design of a sponge and cleaning pad stand in accordance with the present invention;

FIG. 2 is a perspective view of the sponge and cleaning pad stand in use;

FIG. 3 is a front side elevation view of the sponge and cleaning pad stand of FIG. 1;

FIG. 4 is a rear side elevation view of the sponge and cleaning pad stand of FIG. 1;

FIG. 5 is a left side elevation view of the sponge and cleaning pad stand of FIG. 1;

FIG. 6 is a right side elevation view of the sponge and cleaning pad stand of FIG. 1;

FIG. 7 is a top side plan view of the sponge and cleaning pad stand of FIG. 1; and,

FIG. 8 is a bottom side plan view of the sponge and cleaning pad stand of FIG. 1.

The broken lines shown in the drawings represent portions of the sponge and cleaning pad stand that form no part of the claimed design. The broken lines seen in FIG. 2 represent environment of use and form no part of the claimed design.

1 Claim, 8 Drawing Sheets
